Primary Examiner — Lakiya G Rogers*Assistant Examiner* — Carissa C Fitts(74) *Attorney, Agent, or Firm* — Hudak, Shunk & Farine Co., LPA(57) **CLAIM**

The ornamental design for an “ankle brace support,” as shown and described.

DESCRIPTION

FIG. 1 is a right top perspective view of an ankle brace showing my new design;

FIG. 2 is a left top perspective view thereof;

FIG. 3 is a right bottom perspective thereof;

FIG. 4 is a left bottom perspective thereof;

FIG. 5 is a right side view thereof;

FIG. 6 is a left side view thereof;

FIG. 7 is a front view thereof;

FIG. 8 is a rear view thereof;

FIG. 9 is a top view thereof; and,

FIG. 10 is a bottom view thereof.

The broken lines in the drawings depict portions of the ankle brace that form no part of the claim.
